Primary Examiner—Sandra L. Morris**Assistant Examiner**—Nanda Bondade**Attorney, Agent, or Firm**—Bryan Cave LLP**[57]****CLAIM**

The ornamental design for a front face of speaker disguise, as shown and described.

DESCRIPTION

FIG. 1 is a front elevation view of the front face of the speaker disguise showing my new design, wherein the broken line showing the outline of a speaker is for illustrative purposes only and forms no part of the claimed design.
